UNITED STATES PATENT OFFICE

CARLTON JONES HAKES, OF SPENCER, IOWA

TOOL FOR CLEANING TUBES

Application filed May 23, 1932. Serial No. 613,125.

The object of my invention is to provide a tool of this character of simple, durable and inexpensive construction to quickly and easily remove from the interior of the tube 5 deposits or scales of such material as carbon, lime, rust, etc., with a minimum number of movements and by the combined action of cutting the deposit or scale mechanically and carrying it away by fluid pressure.

10 More specifically it is the object of my invention to provide a tool of this character with the cutting edge at the forward end of the tool and a series of cutting edges extending around the tool throughout the major portion of its body, said parts being so arranged that at times all of the cutters throughout the body will engage and operate upon the deposit or scale within a tube being cleaned.

15 My invention consists in the construction, arrangement and combination of the various parts of the device, whereby the objects contemplated are attained, as hereinafter more fully set forth, pointed out in my claims, and 20 illustrated in the accompanying drawing, in which:

25 Figure 1 shows a side elevation of a tube cleaning tool embodying my invention and shown in position within a tube having a deposit or coating of material to be removed from the tube, and showing the front end of the tool sprung together to position where each of the cutting edges will successively engage portions of the deposit or scale to be 30 removed.

35 Figure 2 shows a longitudinal sectional view of my improved cutting tool; and

40 Figure 3 shows a sectional view on the line 3—3 of Figure 2.

45 Referring to the accompanying drawing, I have shown a tool embodying my invention and comprising a body portion 10 preferably made of spring metal and formed hollow. At one end it is detachably connected to a fluid pressure pipe 11. At the opposite end of the tool its inner surface is beveled to form a cutting edge at 12, at its forward outer edge.

50 Arranged along the exterior of the body at spaced intervals is a series of ribs 13 ar-

ranged circumferentially and having both their forward and rear edges formed with cutting edges at 14.

At the opposite sides of the cutting tool I have formed slots 15 extending from the forward end of the tool to a point near the rear end thereof and beyond the last of the ribs 13, for purposes hereinafter made clear.

In Figure 1 of the drawing I have shown a tube 16 having a deposit or layer 17 of foreign material to be removed from the tube, and which may be carbon, lime, rust or the like.

In practical operation with my improved tube cleaning tool, the forward end of the tool is inserted in the tube to be cleaned and means for applying fluid pressure is provided at the other end of the tube. Then the operator grasps the tool or the pipe 11 communicating with the interior of the tool and manually moves the tool forward and backwardly through the tube to be cleaned. If the layer 17 of material to be cleaned from the tube is relatively hard and thick, then the front cutting edge 12 alone will not remove 70 all of it, but only the inner surface thereof, and this will cause the opposite sides of the tool to be sprung together, as shown in Figure 1, and when in this position each of the succeeding forward cutting edges 14 of the ribs 13 75 will also cut or scrape parts of the layer 17 from the interior of the tube, and by this means with each one of the cutting edges removing a small portion of the deposit, the tube may be effectively cleaned with a minimum of reciprocating operations of 80 the tool.

85 During the reciprocating movement of the tool, to loosen the deposit or scale, fluid under pressure is passed through the tube 11 and out through the sides of the slots 15, and through the grooves between the slots, so that as fast as the deposit 17 is removed by the cutting edges 14, the material will drop into the slots and be carried away by the fluid, due 90 to the fact that the slots 15 are in communication with the spaces between the ribs, as clearly shown in Figure 1.

I claim as my invention:

1. A tube cleaner comprising a hollow tool 100

body having at one end a circular cutting edge, a series of annular ribs formed on the outer surface of the body with their edges shaped to form cutters, the body of the tool being formed with longitudinal slots extending from its cutting end toward its other end, and arranged with the slots communicating with the spaces between the said ribs and whereby fluid pressure on the interior of the tool may pass outwardly through the slots and through the spaces between the ribs to remove scale therefrom.

2. A tube cleaner comprising a hollow tool body having at one end a circular cutting edge, a series of annular ribs formed on the outer surface of the body with their edges shaped to form cutters, the body of the tool being formed with longitudinal slots extending from its cutting end toward its other end, and arranged with the slots communicating with the spaces between the said ribs and whereby fluid pressure on the interior of the tool may pass outwardly through the slots and through the spaces between the ribs to remove scale therefrom, the tool being made of spring metal so that the sides thereof may be sprung inwardly and outwardly to enter tubes having more or less scale, and whereby each of the ribs may at times engage and cut scale with the tube being cleaned.

3. A tube cleaner comprising a hollow tool body having at one end a circular cutting edge, a series of annular ribs formed on the outer surface of the body with their edges shaped to form cutters, the body of the tool being formed with longitudinal slots extending from its cutting end toward its other end, and arranged with the slots communicating with the spaces between the said ribs, and whereby fluid pressure on the interior of the tool may pass outwardly through the slots and through the spaces between the ribs to remove scale therefrom, and a fluid pressure pipe attached to and communicating with the end of the tool opposite the cutting end.

CARLTON JONES HAKES.
